GAS-CLEANING PRECIPITATOR

Gaylord W. Penney, 216 Louis Road, Pittsburgh 35, Pa.

Filed Jan. 8, 1958, Ser. No. 707,788

17 Claims. (Cl. 183—7)

My invention relates to electrical precipitators for atmospheric dust, and particularly to two-stage precipitators comprising an ionizing stage for ionizing the particles which are to be precipitated, a collector-stage for precipitating the ionized particles, and a means for causing the gas to pass first through the ionizing stage and then through the collector-stage, as is broadly covered in my Patent No. 2,129,783, granted September 13, 1938.

The present invention relates more particularly to the collector of such a two-stage gas-cleaning unit, specifically a novel close-spaced collector. At any given voltage-gradient in the precipitating spaces between the collector-plates, the volume (cubic feet) of air which can be cleaned per minute is approximately directly proportional to the total area of the dust-collecting surfaces of the collector-plates. It is thus obvious that any reduction in the plate-spacing will reduce the volumetric size of the collector.

My above-mentioned patent on a two-stage gas-cleaning unit recommended the use of collector-plates in the form of large-area metal sheets of sufficient thickness and stiffness to be able to stand on edge without excessive warping in a lateral direction, and this has been the conventional collector-construction ever since. With the collector-plates of a reasonable flatness or freedom from warping, and of a reasonable surface-area, the normal plate-spacing in commercial two-stage gas-cleaning units has been from .31 to .38 inch, so as to safeguard against short-circuits between successive plates, although one manufacturer has made a collector having a plate-spacing of .19 inch, which is generally regarded as the limit, or past the limit, with the standard type of collector-cell construction.

My present invention involves a close-spaced collector, comprising closely spaced precipitator-plates which are individually so flexible as to be non-self-supporting in a lateral direction, and which are held apart by a plurality of spacer-means, preferably in the form of rows of spacer-strips, extending in the direction of gas-flow, and spaced laterally from each other at frequent intervals across the faces of the precipitator-plates. This makes possible the use of thinner and less expensive plates, using the term "plates" as meaning any thin, extensive-surface electrodes having sufficient conductivity to maintain a prescribed voltage-gradient across the precipitating spaces, said "plates" being either flat, cylindrical, or spiral, or of any other shape which permits the maintenance of a reasonably uniform spacing between adjacent "plates."

This new type of collector-construction is adapted to quite small spacings, preferably of the order of .02 to .06 inch, or say between the limits of .015 and .08 inch. This makes possible a considerable reduction in the size or space-requirements of the collector.

My new close-spaced collector requires a power-supply means which includes individual circuit-means for the precipitating spaces between the plates, for supplying limited amounts of unidirectional current to said plates

2

to maintain a predetermined range of potential-gradients in the precipitating spaces. It is necessary that these individual circuit-means shall include sufficient resistances to confine the serious deleterious operative effects of an accidental short-circuit between any two successive plates to the immediate vicinity of the short-circuited portion, without imposing an excessive drain on the power-supply means. These provisions are necessary, because the closeness of the plate-spacings and the flexibility of the individual precipitator-plates are such as to make an accidental short-circuit an expectable contingency which must be provided for in the design.

My novel close-spaced collector-cell construction can be of either one of two general types, depending upon the high-resistance circuit-means which are used to supply the tiny plate-charging currents.

In my series-cell construction, which at present seems to be the preferred form, a plurality of cells, or precipitating spaces between successive plates, are disposed in series with each other, between two relatively widely spaced electrode-plates between which a unidirectional voltage-difference is maintained, and the spacers are made of semiconductor material, so as to draw a "leakage"-current which is large, compared to the collected current which is due to the charges on the particles which are precipitated from the gas. The electrode-plates must necessarily be of a sufficiently good conductivity to have only small voltage-drops across all parts of their entire areas, but the intermediate plates are preferably of semiconductor material such as treated paper or the like, as will be subsequently explained.

My close-spaced collector may also be made in a parallel-cell construction, in which the cells are all connected in parallel across a common voltage-source, the plates are all good-conductor electrode-plates, and the current-limiting resistances are connected between the individual plates or cells and the voltage-source.

The result of my close-spaced collector-construction is a reduction in cost, weight, and space-requirements, and other advantages which will be described hereinafter.

The essential principles of my invention will better be understood from the following description of two exemplary forms of embodiment which are shown in the accompanying drawings, wherein

Figure 1 is a reduced-scale diagrammatic horizontal sectional view of a complete air-cleaning unit rated at approximately 600 c.f.m. (cubic feet per minute), in a preferred exemplary form of construction, the section-plane being indicated at I—I in Fig. 2.

Fig. 2 is a diagrammatic transverse or vertical sectional view of the same unit, as viewed from the ionizing-stage end, the section-plane being indicated at II—II in Fig. 1.

Fig. 3 shows, on a magnified scale, with parts broken away, a diagrammatic transverse sectional view of one of the two series-cell collector-units of Fig. 1, the section-plane being indicated at III—III in Fig. 1.

Fig. 4 is a reduced-scale diagrammatic front-elevational view of a four-part metal-plate parallel-cell collector-unit, such as could be substituted for one of the two two-part series-cell collector-units of Fig. 1, as viewed from a section-plane in the position indicated approximately by the broken line A—A in Fig. 1, the reduced scale of Fig. 4 being somewhat larger than the reduced scale of Fig. 1, the section-plane of Fig. 4 being indicated at IV—IV in Fig. 5.

Fig. 5 is a full-scale diagrammatic transverse or vertical sectional view, with parts broken away, through a four-part metal-plate collector-unit such as is shown in Fig. 4, the section-plane being indicated at V—V in Figs. 4 and 6, and

Fig. 6 shows, on a magnified scale, with parts broken away, a diagrammatic horizontal sectional view of the four-part metal-plate collector-unit, on a section-plane which is shown at VI—VI in Figs. 4 and 5.

Figs. 1 and 2 show an exemplary form of construction of a complete air-cleaning unit embodying my invention. It is disposed within an open-ended piper or housing 1, having a blower 2 therein for moving the air or other gas to be cleaned, as shown by the arrows. The cleaner is a two-stage precipitator, comprising an ionizing stage 3 and a collector-stage 4 through which the air successively passes. The ionizing stage 3 may be any means for ionizing the "dust"-particles which are to be removed from the air. It is shown in a familiar form comprising a plurality of positively charged fine wires 5 which are stretched across the air-stream between elongated grounded electrodes 6a, 6b, 6c, 6d, so that corona from the fine wires will positively charge, or ionize, the dust-particles.

According to my present invention, the collector-stage 4 comprises one or more of my novel close-spaced collectors, for collecting, or precipitating out, the ionized dust-particles. It is shown as comprising two identical collector-units 7 and 8, mounted at an angle to the main air-stream, in a familiar V-form, so that the air-velocity of the air-stream in the housing 1 can be greater than the air-velocity through the collector-units 7 and 8, although I am not limited to this detail.

The general contours of the two close-spaced collector-units 7 and 8 will be apparent from Figs. 1 and 2, while the details of their construction are shown in a magnified representation in Fig. 3. As shown in Fig. 1, each of the collector-units 7 and 8 is made in two separate identical parts 7', 7'' and 8', 8'', respectively, the two parts of each unit being serially connected, one behind the other, so that the air passes first through one part and then through the other, as it passes through the respective collector-units. While I am not limited to this two-part construction, it has significant advantages in my close-spaced cell-construction, as will be subsequently explained.

As shown in Figs. 1 and 3, each of the parts 7', 7'', 8' and 8'' of the two close-spaced collector-units 7 and 8 comprises a stack of closely spaced "plates" (as previously defined), each plate being a flat sheet of material having a certain amount of electrical conductivity, the planes of the plates being parallel to the paths of air-flow through the respective collector-units, so that the ionized dust can be precipitated out of the air-streams as the air passes through the precipitating spaces 9 between successive plates. The particular collector-units 7 and 8 which have been chosen for illustration have a stack of two hundred twenty-nine plates, numbered from P1 to P229, in each of the four component parts 7', 7'', 8' and 8''. Every thirty-eighth plate, namely each of the plates P1, P39, P77, P115, P153, P191 and P229, is an electrode-plate of good-conducting material such as a metal foil or a foil-coated paper. The intermediate plates do not need to be of good electrical conductivity, and in my preferred construction they are of a semiconducting material such as a semiconducting paper which is available on the market, or ordinary paper soaked in tricresyl phosphate or other semiconducting impregnating material.

It is a characteristic feature of my invention that the collector-plates, such as P1 to P229, are closely spaced, so closely spaced that it is necessary to hold the plates apart by suitable means such as rows of spacer-strips S1 to S26, extending through each of the precipitating spaces 9 in the direction of air-flow, these spacer-strips being spaced laterally from each other at frequent intervals across the faces of the collector-plates as shown in Fig. 3. And since such spacer-strips are used, it now becomes possible to depart from the collector-construction which has heretofore been standard, which used relatively rigid plates which would maintain their spacings

over relatively large precipitating-areas which were not broken up by intermediate spacers. It now becomes possible for me to use very thin, flimsy "plates," which are cheaper, lighter in weight, and space-saving, plate for plate. Further, for my semiconducting plates, P2 to P38, P40 to P76, and the like, I can use treated paper, or other inexpensive thin sheet-material having semiconductor-properties, so that the entire collector-unit becomes so inexpensive that it may be thrown away when it becomes too dirty from an accumulation of collected "dust."

When my close-spaced collector uses a plurality of cells (or precipitating spaces 9 bounded by plates), which are electrically connected in a series-circuit connection 15 between two electrode-plates P1, P39, or P39, P77, etc., it is necessary for the spacer-strips S1 to S26 to be made of semiconducting material, so that the spacer-strips will draw, from the electrode-plates, a "leakage"-current which is large, compared to the collected current which is carried by the charges on the dust-particles which are deposited on the several collector-plates; as otherwise the collected charge particles would build up electrostatic fields which, in the first second of operation, would start to break up the even distribution of the total voltage-20 difference between the serially connected cells between the successive electrode-plates, and the collector would become inoperative or ineffective.

In my preferred series-cell collector-construction which is shown in Figs. 1 and 3, the spacer-strips S1 to S26 30 are made of cardboard which has been treated to make it a semiconductor, or said strips may be made of semiconducting rubber, plastic, or any other materials having the necessary high resistance. A preferred collector-design may use, for example: metal foils, or thin metal sheets about .005 or .006 inch thick, for the electrode-plates P1, P39, etc.; paper about .003 inch thick for the intermediate plates P2-P38, P40-P76, etc.; and cardboard for the spacer-strips S1 to S26. In the course of assembling such a collector, the cardboard spacer-strips 35 may be cemented to the paper sheets and to the metal foils by some adhesive such as shellac; and the assembly may then be soaked in tricresyl phosphate, which is a fire-retardant, gives the desired degree of conductivity, and acts as an adhesive to hold the collected dust. Other materials and assembly-methods may be used, however.

In practice, the blower 2 of Fig. 1 produces a blower-pressure such as to cause a suitable air-velocity of the order of $V=250$ or 300 f.p.m. (feet per minute) in the precipitating spaces 9 of the collectors 7 and 8. This 40 velocity should not be high enough to blow the collected dust-particles off of the plate-surfaces, nor yet so low as to make an uneconomical construction. The total "face"-area A of the collectors (at right angles to the air-flow), in square feet, will then determine the rated air-handling 45 capacity of the collectors, namely VA cubic feet per minute (c.f.m.).

My collector is preferably characterized by a very small plate-spacing of the order of .02 to .06 inch, or, say, between the extreme limits of .015 and .08 inch. The 50 necessary length L of the collector-unit, in the direction of airflow, is dependent upon the plate-spacing, because the time required for the positively charged particles to drift to the negative plate-surface of each precipitating space depends upon the distance between the positive 55 and negative plates. Due to the close spacing of the plates, the total length of my collector-unit in the direction of air-flow need be only 2 or 3 inches.

When the air-cleaning precipitator is put into operation, a suitable positive unidirectional ionizing-voltage, 60 such as 13 kv. (kilovolts), for example, is applied to the ionizing wires 5, as diagrammatically indicated in Fig. 1; and a suitable positive unidirectional precipitating-voltage, which may for convenience be the same as the ionizing-voltage, is applied to tabs 10 on the alternate 65 electrode-plates P39, P115 and P191 of the series-cell

collector-units 7 and 8 of Fig. 1, the number of serially connected cells being so chosen as to provide a suitable voltage-gradient of about 6,000 to 10,000 volts per inch (more or less), in the precipitating spaces 9. It is to be understood that the negative terminal of the unidirectional voltage-source is grounded, said source being diagrammatically indicated simply by the legends, +13 kv. The electrode-plates P1, P77, P153 and P229 are indicated as being grounded.

In the air-cleaning precipitator shown in Figs. 1 and 2, the ionizing wires 5 of the ionizing stage 3, and the collector-plates P1 to P229 of the two collector-units 7 and 8 extend vertically; and the top and bottom walls of the housing 1 are lined on the inside, with insulating sheets 11 and 12, respectively, in the collector-stage of the precipitator, to prevent the short-circuiting of the top and bottom edges of the collector-plates. The two outer elongated grounded electrodes 6a and 6d of the ionizing stage lead the ionized dust-laden air to the front edges of the entrance-faces of the two collector-units 7 and 8, respectively, at the wide ends of the V which is formed by said units, as shown in Fig. 1. The point of the V is illustrated as being closed by a vertical guide or baffle 13, so that the air is forced to divide equally between the two collector-units 7 and 8.

The close-spacing of my collector-plates, about .04 inch in the illustrated equipment, tends to increase the air-pressure drop across the collector-units, as the air passes through the same; but this increase in pressure-drop is reduced somewhat by the considerable decrease in the collector-length L, which, in the illustrated equipment, totals only about 3 inches as measured in the direction of air-flow through each of the collector-units 7 and 8. This air-pressure drop, due to air-friction in the narrow precipitating spaces 9 in the illustrated equipment, represents a pressure-drop of the order of .08 inch of water, which is not at all objectionable. In fact this much pressure-drop in the collector-units is advantageous in causing the air to distribute itself uniformly over the entrance-faces or "face"-areas of the two collector-units 7 and 8, thereby avoiding the previously experienced necessity of introducing air-baffling means for causing the air to divide evenly in all the previously used wide precipitating-spaces between the collector-plates.

The positively charged dust-particles which are collected on the negative plate-surfaces of the precipitating plates tend to charge said plates at a rate which is dependent upon: (a) the amount of particulate matter which was originally carried by the air, (b) the average particle-diameter, and (c) the average number of electronic charges which are carried by each dust-particle after the air has passed through the ionizing stage 3. The charge which is thus collected on the collector-plates, in cleaning very hazy or smoky air, may be typically figured at something of the order of .003 microampere per c.f.m.

In the particular series-cell collectors 7 and 8 which are shown by way of illustration in Figs. 1 to 3, the high potential-difference (13,000 volts) which is maintained between successive electrode-plates, such as P1 and P39 for example, is subdivided into thirty-eight equal parts in the thirty-eight intermediate precipitating-spaces 9, by means of twenty-six stacks of semiconducting spacer-strips S1 to S26, which are built up between these two electrode-plates, these spacers acting as potentiometers for subdividing the total voltage. As in other potentiometer-applications, it is necessary for these spacer-strip potentiometers to draw a leakage current which is large, say 100 times, or between 10 and 1000 times, the current which is collected by those portions of the collector-plate surface-areas which are to be kept at a prescribed potential by each portion of the spacer-strip potentiometers. At a leakage-current which is 100 times a maximum collector-load of, say, .003 microampere per c.f.m., or .9 microampere per square foot of collector "face"-area, said leakage-current becomes .3 microampere per

c.f.m. of collector-rating, or 90 microamperes per square foot of face-area. The leakage-power, drawn by the collectors 7 and 8 of Fig. 1, would then be something like $.3 \times 10^{-6} \times 13 \times 10^3$, or .004 watt per c.f.m. This is to be compared to a typical ionizer-power which is consumed by corona in the ionizing wires 5, which may vary between about .01 and .04 watt per c.f.m., according to the design.

In a close-spaced paper-cell collector having spacer-strips S1 to S26 which are 3 inches long, .09 inch wide, and .04 inch thick, spaced .62 inch between center-lines of successive spacers, an acceptable resistivity of both the paper-plates and the spacer-strips will be something of the order of 3×10^9 or 5×10^9 ohms per inch-cube.

It will be understood, of course, that the foregoing specific figures are only by way of illustration or example, as my invention is not limited to any specific figures except within the ranges indicated.

A characteristic feature of my close-spaced collector-design is that the individual precipitator-plates are so flimsy or flexible, and they are spaced so closely together, that an accidental short-circuit between plates will be an expectable contingency, which must be so provided for, in the design, that the air-cleaning efficiency will be only minutely reduced by such a short-circuit, and that the protective high resistances which are necessarily introduced in the design shall not result in an excessive power-consumption, either during normal fault-free operation or during the existence of one or more short-circuits. In my series-cell paper-plate design which has just been discussed, it has been shown that the leakage-power is quite acceptably small, and this is true whether there is a short-circuit or not, because the successive plates can be impressed with only such potential-differences as are furnished by the semiconductor spacer-strips.

As to the air-cleaning efficiency during a short-circuit between adjacent collector-plates, the high resistivity of the semiconductor paper-plates means that if two normally spaced plates should touch at some intermediate point between two semiconductor spacer-strips, the potential-difference between these two plates will approach zero only at the precise line of contact, or point of contact, as the case may be; because the high resistance of the plates, traversed by the tiny short-circuit current, will produce voltage-drops which will cause the potential-difference to become normal in the vicinity of the two spacer-strips, even though the potential-difference should become zero at the intermediate short-circuited point or line of contact, as the case may be. Thus, a short-circuit will cause the dust-precipitating potential-gradient to be lost, or reduced, over only a very small proportion of the total dust-collecting area of the total number of collector-plates, and furthermore the air-flow will be substantially reduced at the faulted point, so that the over-all cleaning efficiency will remain high.

Since, however, my close-spaced collector-unit, (unlike standard previous commercial designs), is intended to operate while there are one or more short-circuits in it, it is usually desirable, and worth the trouble, to break the total length of air-travel in each collector-unit into two half-as-long air-paths in series. Then it will be highly improbable that both half-length sections will be short-circuited for any given air-path through the collector-unit. Thus, in Fig. 1, the three-inch-long collector-unit 7 is divided into two separate parts 7' and 7", each 1½ inches long in the direction of air-flow, the part 7" being placed behind the part 7' in the direction of air-flow. The air-flow from the part 7' to the part 7" may be secured by means of lateral confining-guides or baffles 14 and 15. In like manner, the unit 8 is divided into two parts, 8' and 8". This subdivision of the collector-units into a plurality of serially connected parts (in the direction of air-flow) is quite effective, because most of the air-cleaning which is accomplished by any collector-unit is performed in the first half of its length.

in the direction of air-flow, so that a section of half the length of the complete unit will have an air-cleaning efficiency not too much less than the whole complete unit.

The close-spaced series-cell paper-plate collector-units 7 and 8 of Fig. 1 have the advantage of disposability, as well as certain functional advantages, as have been described; but in some applications it may be a disadvantage that these paper-cell units are not normally cleanable.

In Figs. 4 to 6, therefore, I have shown a close-spaced metal-plate collector-unit 17 which may be substituted for one of the paper-plate units 7 or 8 of Fig. 1, and which can be cleaned with a vacuum cleaner, or by washing with oil, or by other methods.

Instead of having a large number of plates in series, with their potentials determined by a limited conductivity of spacers, the use of metal plates introduces the possibility of using spacers which are insulating, with alternate plates at ground and at a higher potential. With close spacing between these plates in accordance with my present invention, the difference in potential between adjacent plates will preferably be of the order of 300 volts, as compared to 6000 volts in wide-space units of a previously standard design. At this low potential, it is quite feasible to feed the 300-volt plates through a strip or block of semiconductor-material.

In the metal-plate collector-design shown in Figs. 4 to 6, a large number of thin, rather flimsy, metal or other good-conductor plates p_1 to p_{229} are spaced by spacer-strips s_1 to s_{26} in much the same manner as described for Figs. 1 to 3, except that each of the spacer-strips s_1 to s_{26} is an insulator which draws a negligibly small leakage-current. The metal plates p_1 to p_{229} may all be similar to the electrode-plates P1, P39, P77, P115, P153, P191 and P229 of Figs. 1 and 3. In Figs. 4 to 6, the odd-numbered plates, from p_1 to p_{229} , are grounded, as by being electrically connected to a grounded wire 18, and the even-numbered plates, from p_2 to p_{228} , are connected to a positive wire or conductor 19 through high-resistance connections which may advantageously be obtained by contacts between the tabs of the various plates and a semiconductor-envelope 20 which surrounds the positive wire 19. The positive wire 19 is diagrammatically illustrated as being energized from a unidirectional source of suitable voltage, such as +300 v., so as to maintain a desirable potential-gradient in the precipitating spaces 9 between successive plates such as p_1 and p_2 , or between p_2 and p_3 , and so on.

Assuming the same plate-spacing as in Figs. 1 to 3, the collector-unit 17 is Figs. 4 to 6 works very well (for example) with a resistance of 10^8 ohms per c.f.m. handled, in series with each of the positively charged even-numbered plates, from p_2 to p_{228} , this resistance being obtained by the semiconducting covering 20 on the wire 19. The maximum collected current in each positive plate, when cleaning the air in a very smoky or hazy room, may be something like 4.5×10^{-9} amperes per plate per c.f.m. handled. Assuming this to be true, the voltage-drop through a resistance of 10^8 ohms, in normal operation, will be $4.5 \times 10^{-9} \times 10^8$ or .45 volts, which is quite negligible as compared to an applied potential of 300 volts.

In case of a short-circuit in the metal-plate collector, the current in the short-circuited positive plate would be $300/10^8$ ampere or 3 microamperes per c.f.m. of the normal rating of that plate, and the energy dissipated in each short-circuit will be 0.0009 watt per c.f.m., which is quite safe. As long as the number of short-circuits is small, the effect on efficiency is small, because the large number of sound or unfaultered plates makes it possible to clean very nearly 100% of the air.

In the metal-plate collector-construction which is shown in Figs. 4 to 6, a short-circuit affects the total precipitating or dust-collecting area of the faulted plate, because the plate is a good conductor. For this reason, it is de-

sirable to subdivide each plate into relatively small sections, in order to localize any short-circuit. In order to illustrate the principle of such a procedure, I have subdivided the collector-unit 17 into two equal parts 17a and 17b, thus halving the vertical dimension of each plate; with two lateral confining-guides or baffles 21 and 22 being added to prevent air-escape between these two parts, as shown in Fig. 5. This subdivision is in addition to the previously described subdivision in the direction of air-flow. Thus, the metal-plate collector-unit of Figs. 4 to 6 is subdivided into four parts 17a', 17b', 17a'' and 17b'', with the double-primed parts back of the correspondingly lettered primed parts, and with the b parts above the corresponding a parts.

The limits of resistance, voltage and plate-spacing, which have been given hereinabove, are for my preferred design. The most important objects of my present invention are to devise a small-cost, small-volume, low-power precipitator-unit of close-spaced plate-construction, which is simple to manufacture and trouble-free in service. The leakage-surfaces at the sides SS and ss of my spacers S1 to S26 and s1 to s26, in Figs. 3 and 5, are substantially normal to the plate-surfaces, thus making a simple construction. The plate-spacing, which is determined by the thickness of the spacers, is made quite small, so that the voltage-difference between successive plates may also be made quite small because of the reduced distance which the precipitated dust-particles must travel, in the precipitating spaces between the plates. By making the plate-spacing less than 0.1 inch, and at the same time suitably reducing the voltage-difference between successive plates, I am enabled to use these normal leakage-surfaces SS and ss without entailing excessive surface-leakage currents such as have hampered previous attempts at a close-spaced precipitator-unit.

An essential feature of my invention is the use of resistances which will carry the small charging-currents which are necessary to maintain the requisite plate-to-plate voltages in the precipitator-unit, while at the same time suitably limiting the energy which is dissipated in an accidental short-circuit between any two successive plates; thus making it practicable to use a close-spaced, flexible-plate collector in which an accidental short-circuit is an expectable contingency which must be provided for in the design. If the energy dissipated in any such short-circuit is less than 0.05 watt, or even less than 0.1 watt, these objectives can readily be obtained, involving no energy-dissipating difficulties in order to avoid a fire-hazard or even a hot-spot. Actually, in the embodiments of my invention which have been illustrated in the accompanying drawings, the energy-loss per short-circuit is very much smaller than 0.05 watt. It might be stated, therefore, that the plate-spacing should be less than 0.1 inch, the plate-to-plate voltage should be less than 1000 volts, and the energy consumed in each short-circuit should be less than 0.1 watt; or these limits could be more conservatively stated as 0.08 inch, 600 volts, and 0.05 watt, respectively. My preferred design is considerably more conservative yet.

While I have described and illustrated my invention in two different forms of embodiment, and while I have given specific exemplary possible or preferred details of the design, I wish it to be understood that my invention, in its broadest aspects, is not limited to these embodiments and these details.

65 I claim as my invention:

1. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a close-spaced collector comprising a plurality of closely spaced precipitator-plates which are individually so flexible as to be non-self-supporting in a lateral direction, the space be-

tween said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to maintain a predetermined range of potential-gradients in said precipitating spaces, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the closeness of the plate-spacings and the flexibility of the individual precipitator-plates being such as to make an accidental short-circuit an expectable contingency which must be provided for in the design.

2. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a plurality of close-spaced collectors disposed one after another in the path of gas-flow, each collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to maintain a predetermined range of potential-gradients in said precipitating spaces, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the closeness of the plate-spacings and the flexibility of the individual precipitator-plates being such as to make an accidental short-circuit an expectable contingency which must be provided for in the design.

3. A close-spaced collector adapted for use in a two-stage gas-cleaning precipitator, said collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to maintain a predetermined range of potential-gradients in said precipitating spaces, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the closeness of the plate-spacings and the flexibility of the individual precipitator-plates being such as to make an accidental short-circuit an expectable contingency which must be provided for in the design.

4. The invention as defined in claim 3, characterized

by the average precipitating spacing being within the limits of 0.015 and 0.08 inch.

5. A close-spaced collector adapted for use in a two-stage gas-cleaning precipitator, said collector comprising a plurality of closely spaced precipitator-plates which are individually so flexible as to be non-self-supporting in a lateral direction, the spaces between said precipitator-plates extending in the direction of gas-flow; a plurality of high-resistance spacer-means for holding successive precipitator-plates in closely spaced relation, said spacer-means being disposed at spaced intervals, spaced laterally of the direction of gas-flow; and a power-supply means for maintaining a uni-directional potential-difference between two relatively widely separated plates whereby there are a plurality of serially connected high-resistance spacer-strips between the plates having said potential-difference; the resistance of said spacer-strips being such that the spacer-strips draw a leakage-current which is large, compared to the collected current which is due to the charges on the particles which are precipitated from the gas; the closeness of the plate-spacings and the flexibility of the individual precipitator-plates being such as to make an accidental short-circuit between two successive plates an expectable contingency which must be provided for in the design.

6. A close-spaced collector adapted for use in a two-stage gas-cleaning precipitator, said collector comprising a pair of relatively widely separated electrode-plates of relatively good conductivity; a stack of closely spaced semi-conducting precipitator-plates which are individually so flexible as to be non-self-supporting in a lateral direction, the spaces between said precipitator-plates extending in the direction of gas-flow, said stack of closely spaced precipitator-plates being disposed between said electrode-plates; a plurality of high-resistance spacer-means for holding successive precipitator-plates in closely spaced relation, said spacer-means being disposed at spaced intervals, spaced laterally of the direction of gas-flow; and a power-supply means for maintaining a unidirectional potential-difference between said electrode-plates; the resistance of said spacer-strips being such that the spacer-strips draw a leakage-current which is large, compared to the collected current which is due to the charges on the particles which are precipitated from the gas; the closeness of the plate-spacings and the flexibility of the individual precipitator-plates being such as to make an accidental short-circuit between two successive plates an expectable contingency which must be provided for in the design.

7. A close-spaced collector adapted for use in a two-stage gas-cleaning precipitator, said collector comprising a plurality of closely spaced good-conducting precipitator-plates which are individually so flexible as to be non-self-supporting in a lateral direction, the spaces between said precipitator-plates extending in the direction of gas-flow; a plurality of substantially insulating spacer-means for holding successive precipitator-plates in closely spaced relation, said spacer-means being disposed at spaced intervals, spaced laterally of the direction of gas-flow; and a power-supply means, including individual circuit-means for supplying limited amounts of current to said precipitator-plates to maintain a predetermined range of potential-gradients between successive precipitator-plates, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the closeness of the plate-spacings and the flexibility of the individual precipitator-plates being such as to make an accidental short-circuit an expectable contingency which must be provided for in the design.

8. A two-stage gas-cleaning precipitator, comprising an ionizing stage for ionizing the particles which are to

be precipitated, a collector-stage for precipitating the ionized particles, and a means for causing the gas to pass first through the ionizing stage and then through the collector-stage; said collector-stage comprising a close-spaced collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to maintain a predetermined range of potential-gradients in said precipitating spaces, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the average precipitating space between two successive precipitator-plates being less than 0.1 inch, the leakage-surfaces at the sides of the spacer-means being substantially normal to the plate-surfaces, and the range of potential-gradients in the precipitating spaces being so low that tolerably small surface-leakage currents are obtained across the spacer-means.

9. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a plurality of close-spaced collectors disposed one after another in the path of gas-flow, each collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to maintain a predetermined range of potential-gradients in said precipitating spaces, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the average precipitating space between two successive precipitator-plates being less than 0.1 inch, the leakage-surfaces at the sides of the spacer-means being substantially normal to the plate-surfaces, and the range of potential-gradients in the precipitating spaces being so low that tolerably small surface-leakage currents are obtained across the spacer-means.

10. A close-spaced collector adapted for use in a two-stage gas-cleaning precipitator, said collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to main-

- tain a predetermined range of potential-gradients in said precipitating spaces, said individual circuit-means including sufficient resistances to confine the serious deleterious operative effects of an accidental short-circuit between any two successive precipitator-plates to the immediate vicinity of the short-circuited portion, without imposing an excessive drain on the power-supply means; the average precipitating space between two successive precipitator-plates being less than 0.1 inch, the leakage-surfaces at the sides of the spacer-means being substantially normal to the plate-surfaces, and the range of potential-gradients in the precipitating spaces being so low that tolerably small surface-leakage currents are obtained across the spacer-means.
11. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a close-spaced collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to maintain a predetermined range of potential-difference of less than 1000 volts in each of the precipitating spaces, said individual circuit-means including sufficient resistances to limit the energy dissipated in an accidental short-circuit between any two successive precipitator-plates to less than 0.1 watt and to confine the serious deleterious operative effects of such a short-circuit to the immediate vicinity of the short-circuited portion.
12. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a plurality of close-spaced collectors disposed one after another in the path of gas-flow, each collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said plates, for supplying limited amounts of current to said plates to maintain a predetermined range of potential-difference of less than 1000 volts in each of the precipitating spaces, said individual circuit-means including sufficient resistances to limit the energy dissipated in an accidental short-circuit between any two successive precipitator-plates to less than 0.1 watt and to confine the serious deleterious operative effects of such a short-circuit to the immediate vicinity of the short-circuited portion.
13. A close-spaced collector adapted for use in a two-stage gas-cleaning precipitator, said collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; and a power-supply means, including individual circuit-means for the precipitating spaces between said precipitator-plates, for supplying limited amounts of current to said precipitator-plates to main-

in closely spaced relation, said spacer-means being disposed at spaced intervals, spaced laterally of the direction of gas-flow; the average precipitating space between two successive precipitator-plates being less than 0.1 inch; and a power-supply means, including individual circuit-means for the precipitating spaces between said precipitator-plates, for supplying limited amounts of current to said plates to maintain a predetermined range of potential-difference of less than 1000 volts in each of the precipitating spaces, said individual circuit-means including sufficient resistances to limit the energy dissipated in an accidental short-circuit between any two successive precipitator-plates to less than 0.1 watt and to confine the serious deleterious operative effects of such a short-circuit to the immediate vicinity of the short-circuited portion.

14. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a close-spaced collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; the average precipitating space between two successive precipitator plates being less than 0.08 inch; and a power-supply means, including individual circuit-means for the precipitating spaces between said precipitator-plates, for supplying limited amounts of current to said precipitator-plates to maintain a predetermined range of potential-difference of less than 600 volts in each of the precipitating spaces, said individual circuit-means including sufficient resistances to limit the energy dissipated in an accidental short-circuit between any two successive precipitator-plates to less than 0.05 watt and to confine the serious deleterious operative effects of such a short-circuit to the immediate vicinity of the short-circuited portion.

15. A two-stage gas-cleaning precipitator, comprising an ionizing stage for ionizing the particles which are to be precipitated, a collector-stage for precipitating the ionized particles, and a means for causing the gas to pass first through the ionizing stage and then through the collector-stage; said collector-stage comprising a plurality of close-spaced collectors disposed one after another in the path of gas-flow, each collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; the average precipitating space between two successive precipitator-plates being less than 0.08 inch; and a power-supply means, including individual

circuit-means for the precipitating spaces between said precipitator-plates, for supplying limited amounts of current to said precipitator-plates to maintain a predetermined range of potential-difference of less than 600 volts in each of the precipitating spaces, said individual circuit-means including sufficient resistances to limit the energy dissipated in an accidental short-circuit between any two successive precipitator-plates to less than 0.05 watt and to confine the serious deleterious operative effects of such a short-circuit to the immediate vicinity of the short-circuited portion.

16. A close-spaced collector adapted for use in a two-stage gas-cleaning precipitator, said collector comprising a plurality of closely spaced precipitator-plates which are individually so flexible as to be non-self-supporting in a lateral direction, the spaces between said precipitator-plates extending in the direction of gas-flow; a plurality of spacer-means for holding successive precipitator-plates in closely spaced relation, said spacer-means being disposed at spaced intervals, spaced laterally of the direction of gas-flow; the average precipitating space between two successive precipitator plates being less than 0.08 inch; and a power-supply means, including individual circuit-means for the precipitating spaces between said precipitator-plates, for supplying limited amounts of current to said precipitator-plates to maintain a predetermined range of potential-difference of less than 600 volts in each of the precipitating spaces, said individual circuit-means including sufficient resistances to limit the energy dissipated in an accidental short-circuit between any two successive precipitator-plates to less than 0.05 watt and to confine the serious deleterious operative effects of such a short-circuit to the immediate vicinity of the short-circuited portion.

17. A close-spaced collector adapted for use in a two-stage gas-cleaning precipitator, said collector being a cohering mass comprising a pair of relatively widely separated electrode-plates of relatively good conductivity, a stack of closely spaced semiconducting precipitator-plates, the spaces between said precipitator-plates extending in the direction of gas-flow, said stack of closely spaced precipitator-plates being disposed between said electrode-plates, and a plurality of high-resistance spacer-strips, extending in the direction of gas-flow, for holding successive precipitator-plates in closely spaced relation, said spacer-means being disposed at spaced intervals, spaced laterally of the direction of gas-flow.
